(57) **CLAIM**

The ornamental design for a utility bag, as shown and described.

DESCRIPTION

FIG. 1 is a front view of a utility bag showing my new design;

FIG. 2 is a rear view thereof;

FIG. 3 is a top view thereof;

FIG. 4 is a bottom view thereof;

FIG. 5 is a left side view thereof;

FIG. 6 is a right side view thereof; and,

FIG. 7 is a perspective front view thereof.

The broken lines illustrate portions of the utility bag and form no part of the claimed design. The strap is shown with a symbolic break in its length. The appearance of any portion of the article between the break lines forms no part of the claimed design.
